(75) Inventors: **Jack S. Warner; Jason C. Chamberlain**, both of San Jose; **Bradley J. Hamel**, Santa Clara, all of CA (US)

Primary Examiner—Antoine Duval Davis
(74) Attorney, Agent, or Firm—Wagner, Murabito & Hao LLP

(73) Assignee: **Trimble Navigation Limited**, Sunnyvale, CA (US)

(57) **CLAIM**

The ornamental design for a position determining system including pole-mounted communication system, as shown and described.

(**) Term: **14 Years**

DESCRIPTION

(21) Appl. No.: **29/121,013**

(22) Filed: **Mar. 30, 2000**

(51) LOC (7) Cl. **10-04**

(52) U.S. Cl. **D10/65**; D10/78

(58) Field of Search D10/65, 78; 73/128;
340/995; 342/98, 102, 113, 115, 352, 356,
357, 359, 417-421; 364/200, 434, 443,
444, 449, 451, 708.1, 709.11

(56) **References Cited**

FIG. 1 is an upper right front perspective view, of the position determining system including pole-mounted communication system comprising the present invention;
FIG. 2 is a lower left rear perspective view thereof;
FIG. 3 is a right side elevational view thereof;
FIG. 4 is a front elevational view thereof;
FIG. 5 is a left side elevational view thereof;
FIG. 6 is a rear elevational view thereof;
FIG. 7 is a top plan view thereof; and,
FIG. 8 is a bottom plan view thereof.
